GRINDING-MILL.

1,295,291.

Specification of Letters Patent. Patented Feb. 25, 1919.

Application filed April 4, 1917. Serial No. 159,822.

To all whom it may concern:

Be it known that I, JOHAN S. FASTING, a subject of the King of Denmark, residing at Frederiksberg, near Copenhagen, Denmark, have invented certain new and useful Improvements in Grinding-Mills, of which the following is a specification, reference being had to the accompanying drawings, forming a part hereof.

10 This invention relates to the construction of partitions for use in grinding mills and has for its principal object to provide partitions which shall serve their intended purpose and, in addition, shall be of such character as to have a positive conveying action 15 on the material, as to cause it to travel longitudinally through the mill. In accordance with the invention the openings in the improved partitions or rings have surfaces so 20 inclined with relation to one another and to the material that they will lift the material positively and discharge it in such manner as to bring about a positive conveying action thereof, for any given direction of rotation of the mill. Partitions or rings of 25 this sort, of course, will positively prevent, or at least materially retard, the movement of the material through the mill when the mill is rotated in the reverse direction. The 30 present invention is further concerned with the provision of partitions or rings having openings therethrough so formed as to afford a screening action for the material during its movement through the openings. 35 This screening action is secured in accordance with the invention by forming the screening openings of the proper size. A further object of the invention is to construct the screening openings in such a manner 40 as to protect the openings from injury through blows of the grinding bodies and material thereon. This object is achieved by forming the openings adjacent the mid-section of each partition or ring so that the 45 grinding bodies and material can not fall directly against the openings and subject their peripheries to the hammering or peening action which would otherwise occur. Still a further object is to provide a screening 50 partition of the general character described which may be cast readily without danger of burning the cores by providing heavy cores which pass part way through the partition from the opposite faces thereof and are offset in such a manner that they

overlap only where the slot is formed. Cores of this character, as will be understood, are not liable to be burned and so permit screening openings of relatively small size to be cast readily. Further objects of the invention will appear hereinafter in connection with the detailed description of the accompanying drawings, in which—

Figure 1 is a fragmentary detail view in cross-section of a grinding mill illustrating one form of the partition rings.

Fig. 2 is a detail view through portions of two ring sections shown in Fig. 1.

Fig. 3 is a sectional view of a somewhat modified form of ring section constructed in accordance with the invention.

As shown in Fig. 1, the partition is formed in separate sections which are slightly separated from each other at their ends, are supported against the outer wall of the mill α , or its lining α' , and are detachably secured to the drum so as to be capable of easy removal and replacement. Each section is formed with a foot b adapted to rest in a step c placed therefor in the lining, and two adjacent sections are secured together to the outer wall of the mill by a common bolt d , the head of which engages shoulders formed on the partition or ring sections, while the outer end receives a nut e^1 outside of the shell α . In this construction the inner edges of the ring sections are held firmly in alignment by wedges e engaging grooves b' in adjacent ends of adjacent sections and provided with threaded portions e^2 to receive nuts e^3 by which the wedges are drawn firmly into place. In so far as the form, character, relative disposition and means of mounting the several sections of each partition go, changes may be made through wide ranges without departing from the invention. It may suffice here to say that each partition instead of being made of a series of short arcuate ring sections, such as have been referred to, may be formed of a single integral member.

It is the purpose of this application to cover, in principle, the specific type of partition or ring shown in cross-sectional form in the drawings. Each of the rings herein illustrated shows that while free longitudinal movement of the material is permitted by the openings formed therein, this movement may be actually accelerated, and made positive in character, by the inclusion of sur-

faces adjoining the openings in the ribs which shall lift the material with a sort of shovel action and discharge it in such direction as to constantly impel it through the mill for any given direction of rotation of the mill. It will appear further that this shovel action is dependent upon the direction of rotation of the mill and that if such direction be reversed, the improved rings or partitions will either prevent the passage of the material or at least will seriously retard it.

As shown in Fig. 2, each ring section is formed with radial openings *f* between which are bars *g* which are beveled on opposite sides as clearly shown. The openings and bars on opposite sides of the ring sections do not register exactly but are offset with respect to each other so that the central passage *f'* through which the corresponding reversely tapered openings *f* communicate, is of much less width than said openings. The primary effect of such offsetting of the openings and bars is to give them a somewhat shovel-like action on the material either assisting the passage of the material through the rings or retarding it, according to the direction of movement of the ring sections with respect to the line of movement of the material through the drum. Thus with the ring sections moving in the direction indicated by the horizontal arrow in Fig. 2 and the material moving through the drum indicated by the vertical arrow, the rings would have a shovel action in opposition to the direction of movement of the material and would therefore retard the movement of the material somewhat, while if the direction of movement of the rings were reversed the shovel action of the rings would assist the movement of the material. This has been shown to be a fact by actual operation of a mill equipped with such rings.

Another feature of importance realized by the improved construction herein shown, lies in the peculiar formation of the screening openings *f'* proper by which the material in its longitudinal movement is constantly screened. These openings *f'*, it will be observed, are formed at about the mid-section of the rings and an appreciable distance from the opposite faces thereof so that they cannot be subjected to the direct hammer-like blows of the falling material and grinding bodies. Indeed, it will be proper to make the openings *f* of such dimensions that the grinding bodies can never come into direct engagement with the central screening openings *f'*. At all events, by the construction described, the life of each ring is materially increased by the protection thus afforded to the screening openings.

In Fig. 3 the ring section is made up in much the manner described in connection with the form shown in Fig. 2 in that each

ring section is made up of a series of radially extending bars *G* between which are formed openings *F* on the opposite side faces of the ring sections, which openings communicate with one another through a central passage *F'* left between proximate edges of the bars adjacent the mid-section of the rings. In this embodiment, the rings instead of having their edges beveled have them formed straight, that is, at right angles to the direction of movement of the ring. The inclined sides *G'* of the bars *G* effect the desired conveying and these beveled sides are so related to one another and to the rings that when the mill is rotated in one direction the beveled sides of one face of each of the rings will come into play to convey the material through the mill in one direction, while when the mill is rotated in the opposite direction the other beveled sides *G'* on the other side faces of the rings will cause the material to travel in the opposite direction. This may be desirable under some conditions of use. This embodiment retains the screening action described in connection with the form shown in Fig. 2 and embraces all of the advantages of the improved screening openings.

It will be observed, upon examination of the drawing, that the shoveling action of the rings or partitions and the protection of the communicating openings from hammering by the grinding bodies, are brought about by the formation of the radially extended openings or recesses in opposite faces of the partition, which recesses communicate through a narrower radial space at one side of the bottom of each recess, while the two communicating recesses are offset from each other in a circumferential direction, at least one side of each recess, as shown in Fig. 3, or both sides, as shown in Fig. 2, being beveled away from the communicating opening.

The embodiments herein shown while intended to be merely illustrative of suitable partitions or rings for practising the invention and obtaining that conveying action in association with the shoveling action, which constitutes the invention, serve to show clearly that by changing the general cross-sectional outlines of the rings, any desired action of the surfaces on the charge may be obtained. By this is meant that rings may be formed to convey the material in one direction for a given direction of rotation of the mill, while preventing the movement of the material in the opposite direction upon the reversal of the direction of rotation; or, the cross-sectional outline of the rings may be such that the material will be conveyed more readily in one direction than in the other for different directions of rotation of the mill; or, in the remaining condition, may be formed to positively convey the material with equal facility in either direction de-

pending upon the direction of rotation. As suggested, these conditions may be realized by casting the partition in the desired form. The improved partitions or rings may be found of especial advantage for use in combination mills in which grinding bodies of one character are held in one grinding chamber, while grinding bodies of a dissimilar character are held in another chamber to 10 which the material passes from the first named chamber. Under such conditions of use, the openings through the improved rings would necessarily be smaller than the grinding bodies so as to prevent the passage 15 of the grinding bodies therethrough. A manufacturing consideration of importance which has not been referred to hereinbefore and which applies to all of the forms shown, resides in the facility with which the improved partitions may be cast. It is obviously difficult for the screening openings to 20 be cast in partition plates since the cores of such openings are necessarily small and liable to be burned by the heat from the molten metal. The improved construction, 25 however, permits the screening openings to be formed without the provision of special cores therefor since the openings at the opposite faces of the plates are cast with relatively heavy cores and these cores may be so 30 arranged with relation to one another and overlapped, as to insure the formation of

the desired screening opening at the intended place.

I claim as my invention:

1. In a grinding mill, the combination of 35 a rotary shell or drum, a transverse radial partition, and means to secure said partition in place, said partition having openings extended each in a radial direction and formed 40 as recesses in opposite faces of the partition which communicate through a narrower radial space at one side of the bottom of each recess, the two communicating recesses being offset from each other in a circumferential direction and having the side remote from the communicating opening beveled away from such opening.

2. In a grinding mill, the combination of 50 a rotary shell or drum, a transverse radial partition, and means to secure said partition in place, said partition having openings extended each in a radial direction and formed 55 as recesses in opposite faces of the partition which communicate through a narrower radial space at one side of the bottom of each recess, the two communicating recesses being offset from each other in a circumferential direction and having both 60 sides beveled away from the communicating opening.

This specification signed this 15th day of August A. D. 1916.

JOHAN S. FASTING.
